By Hanratty, Jr. Attorney

UNITED STATES PATENT OFFICE.

TEPHAN MORYKwas, OF HOBOKEN, NEW JERSEY.

PORTABLE DARK ROOM.

Application filed September 9, 1921. Serial No. 499,390.

To all whom it may concern:

Be it known that I, TEPHAN MORYKwas, residing at Hoboken, in the county of Hudson and State of New Jersey, have invented certain new and useful Improvements in a Portable Dark Room; and I do hereby declare the following to be a full, clear, and exact description of the invention, such as will enable others skilled in the art to which it appertains to make and use the same.

Photographic negatives are generally developed and fixed in dark rooms in which the work may be observed, but from which actinic light rays are excluded.

15 The invention provides a contrivance possessing all the requirements of a dark room, but which is furthermore portable, light and capable of being reduced to a compact form for convenience of handling and 20 minimizing space and which may be quickly set up for use or folded as required.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and minor details 30 of construction may be resorted to without departing from the nature of the invention.

Referring to the accompanying drawings forming a part of the specification,

Figure 1 is a perspective view of a portable dark room embodying the invention showing the same reduced to compact form.

Figure 2 is a perspective view of the device as it appears when set up for use.

Figure 3 is a vertical longitudinal section 40 on the line 3—3 of Figure 2 looking in the direction of the arrows, and

Figure 4 is a detail horizontal section on the line 4—4 of Figure 3.

Corresponding and like parts are referred 45 to in the following description and designated in the several views of the drawings by like reference characters.

The device comprises a case and a hood, the latter being of suitable textile which 50 will exclude rays of light and which is of such formation as to enclose the head, shoulders and arms of the operator and permit of unhampered performance of the required work incident to developing and fixing 55 photographic negatives.

The case comprises a relatively lower sec-

tion A and an upper section B. These two sections are hingedly connected, as indicated at 1, and when closed are made secure by suitable fastening means, as indicated most 60 clearly in Figure 1. The lower section A is provided with a handle 2 for convenience of carrying and manipulating the device. The lower section A is provided with a hinged front 3 which is adapted to be lowered into 65 horizontal position, as indicated most clearly in Figures 2 and 3. Stays 4 support the front 3 in horizontal position and may consist of cord or flexible connection. The top of the upper section B is provided with an 70 opening fitted with a ruby glass; 5 for the admission of light and excluding actinic rays. Sockets 6 are provided at the upper forward corners of the ends of the lower sections A to receive the ends of a bow 7 75 whereby the upper portion of the hood is supported. A brace 8 connects the upper portion of the bow 7 with the top portion of the upper section B when the latter is in open or vertical position. The brace 8 80 sustains the upper portion of the hood and forms a stay for the bow 7.

The hood 9 is of tubular form and consists of suitable textile and its forward portion is attached to the edges of the sections 85 A and B so as to form a close joint therewith and admit of said sections opening and closing. When the case is closed the hood is contained therein and housed and protected thereby. When the case is open 90 and the device set up for use the parts 7 and 8 support the upper forward portion of the hood. The rear portion of the hood contains an elastic 10 or draw string for contracting the same about the body of the 95 operator after the head, shoulders and the upper portion of the body have been introduced into the hood. The bottom of the lower section A and its front 3 form a shelf or support for receiving the various articles 100 incident to developing and fixing photographic negatives. Provision is had for ventilation while excluding actinic light rays. A tortuous air passage is provided in the front and ends of the upper sections 105 B. The front of the upper section B is provided with a narrow opening 11 which constitutes an air inlet. A similar opening 12 is formed in the inner portion of the front and constitutes an air outlet. The openings 110 11 and 12 are preferably out of line and are connected by means of a tortuous passage 13

which while admitting air excludes light rays. The tortuous air passage 13 is formed by staggered partitions 14. The ends of the upper section B have outer narrow openings 15 for the ingress of air and inner narrow openings 16 for the egress of air. These openings 15 and 16 may be in alignment but are connected by means of a tortuous passage 17 which provides for a free circulation of air while excluding actinic light rays.

Having thus described the invention, what I claim is:—

1. A portable dark room comprising a case including relatively upper and lower sections hingedly connected and a tubular hood connected at its forward edge to the edges of the respective sections and adapted to be held extended thereby and means for drawing the opposite end portion of the hood about the body of the operator.
2. A portable dark room comprising relatively upper and lower sections hingedly connected, the lower section having its front hinged to swing outwardly and downwardly into open position, means for supporting said front in horizontal position and a tubular hood having its forward portion connected to the edges of the respective sections and held extended thereby and having its opposite end portion provided with means for drawing the same close about the body of the operator.
3. A portable dark room comprising relatively upper and lower sections hingedly connected, a tubular hood connected at one end to the edges of the respective sections and adapted to be held extended thereby and

a bow having connection with the forward portions of the ends of the lower sections 40 and adapted to support the upper forward portion of the hood.

4. A portable dark room comprising relatively upper and lower sections hingedly connected, the lower section having its front 45 hinged and adapted to swing outwardly and downwardly, sockets at the upper forward corners of the ends of the lower sections, a bow having detachable connection with the sockets and a tubular hood having its forward end connected to the respective sections and its upper forward portion supported by the said bow.

5. A portable dark room comprising relatively upper and lower sections hingedly 55 connected, the upper section being provided with tortuous air passages and the lower section having its front end to swing outwardly and downwardly, means for supporting said front in horizontal position, a bow detachably connected to the forward end of the lower section, a base between the upper portion of the bow and the front of the upper section and a tubular hood connected at its forward end to the respective sections and 60 having its upper forward portion supported by means of the said bow and brace, the opposite end of the hood being adapted to be drawn close about the body of the operator.

In testimony whereof I affix my signature 70 in presence of two witnesses.

STEPHAN MORYKwas.
